UNITED STATES PATENT OFFICE

2,420,670

DISINTEGRATOR SCREEN

Clarence W. Lanter, Du Page County, Ill., assignor to Birtman Electric Company, a corporation of Illinois.

Application February 23, 1944, Serial No. 523,513

8 Claims. (Cl. 241—86)

1

This invention relates to a disintegrator screen and to a disintegrator in which it is useful.

The ordinary disintegrator screen is a foraminous sheet of metal in which the perforations are separated. In the present invention the disintegrator screen comprises a web of material formed in the usual arced shape and provided with transverse slots instead of perforations. The device will be described particularly in connection with a disintegrator such as is shown in my co-pending applications Serial Nos. 502,754 and 502,755, filed August 17, 1943.

The invention is illustrated in the drawings in which Figure 1 is a front elevation partly in section of a disintegrator; Figure 2 is a side sectional elevation of a disintegrator; Figure 3 is a side view of the screen; Figure 4 is a section taken along the line 4—4 in Figure 3; Figure 5 is a section taken along the line 5—5 in Figure 3; Figure 6 is a section taken along the line 6—6 in Figure 5; and Figure 7 is a side view of a modified form of screen.

The rotor comprises a housing 10 consisting of a top housing 11, and a bottom 12. Disintegration is accomplished by the hammer 14 rotated on the shaft 13 by a motor 15 at an extremely high rate of speed. The rotor is within a disintegrator chamber 16 and a screen 17 is mounted in the chamber about the path of the rotor or hammer.

The screen, as shown in Figure 7, preferably extends completely around the path of the hammer. In the form shown in Figure 7 the screen 17c consists of a web of metal bent to circular form and provided with a series of equally spaced transverse slots 18c extending entirely across the disintegrator chamber and substantially across the web 19 of metal. An unslotted edge portion 20 is left at each edge of the screen and this portion projects into the groove 21 on the inner face of the grinding chamber and is supported by a circular shoulder 22 on the outer face. While this is illustrated as a groove, it may also be a shoulder against which the screen rests or against which it is held by its natural resilience.

It is preferred that the groove 21 have a width greater than the thickness of the screen so that the position of the screen with relation to the hammer may be adjusted. In Figure 2 the screen is shown as provided with an upstanding flange 23 which fits firmly against the inner edge of the groove.

The disintegrator includes a hopper having a hopper opening 31 in the top of the disintegrator, and material feeds from the hopper to the gate

2

32 inside the rotor. Material is ground primarily in the disintegrating zone between the hammer faces 33 and the screen 17.

It has been found that the size of the openings 5 may be determined much more accurately by the use of slots rather than the ordinary round openings, since there is less wear upon the stamping instrument. Furthermore the average distance between openings may be greatly reduced, particularly by reduction of the maximum distance 10 which a particle may travel without striking an opening. It is well known that the openings in the screen serve as grinding surfaces and that the actual particles passing through the openings 15 are very much smaller in diameter than the openings themselves. Therefore, the particles are struck either by the hammer faces or by the edges of the openings many times before being 20 finally demolished into the proper size granules or particles. When slots are used, the effective cutting edge area is greatly increased in ratio to the total area of the openings, even though the total perimeter of the openings may be reduced. This is because the edges of the openings tend 25 to shield themselves and to cause particles to glance off without getting far enough into the opening to produce a firm impact upon a sharp edge.

In the form of screen shown in Figure 3, the 30 screen extends entirely around the hammer path but a portion thereof is provided with a non-perforated band 41 provided with crusher bars 42. These bars are welded to the surface of the screen.

In the form of screen shown in Figure 7, the 35 screen 17c is provided with slots 18c extending the entire circumference of the hammer path.

Figure 6 illustrates a form of screen in which 40 the web opposite the striking face of the slot is slightly depressed. This may be accomplished in stamping, the upper surface of the web being inclined toward the slot. In this way a greater effective striking edge may be secured.

The foregoing detailed description has been 45 given for clearance of understanding only, and no unnecessary limitations should be understood therefrom.

What I claim as new, and desire to secure by Letters Patent, is:

50 1. In a disintegrator, a shaft adapted to be rotated, a hammer mounted on the shaft, a housing defining a disintegrating chamber about the path of the hammer, said housing including a side wall adjacent the hammer, a substantially circular groove in the wall slightly outside the

path of the hammer and having a substantial width, a light-weight resilient disintegrator screen of sheet metal in ring form and having a thickness less than the width of the groove, and a flange upon one edge only of the screen of a height sufficient to secure the screen in said groove, said screen being normally of slightly greater diameter than the mounting groove and held in said spaced relationship at least partially by the resiliency of the ring.

2. A disintegrator as set forth in claim 1, in which the screen extends entirely about the path of the hammer.

3. A disintegrator as set forth in claim 1, in which the screen is provided with a series of transverse equally spaced slots.

4. A disintegrator as set forth in claim 1 wherein said screen comprises a web having parallel transverse slots therein substantially at right angles to the direction of the movement of the disintegrator hammer.

5. A disintegrator as set forth in claim 1 wherein said screen comprises a ring of metal provided throughout the major portion of its circumference with screening perforations.

6. A disintegrator as set forth in claim 1 wherein said screen comprises a web having parallel transverse slots distributed at substantially equal intervals about the entire circumference of the screen.

7. A disintegrator as set forth in claim 1 wherein flange is substantially at right angles to said screen.

8. In a disintegrator, a shaft adapted to be ro-

tated, a hammer mounted on the shaft, a housing defining a disintegrating chamber about the path of the hammer, said housing including a fixed side wall and a removable side wall, with both side walls being adjacent the hammer, a substantially circular groove in the fixed side wall slightly outside the path of the hammer and having a substantial width, a light-weight resilient disintegrator screen in ring form having a thickness less than the width of the groove, and a flange upon one edge only of the screen of a height sufficient to secure the screen in said groove, the opposite edge of the screen being held in operative relationship by contact with said removable side wall, said screen being normally of slightly greater diameter than the mounting groove and held in said spaced relationship at least partially by the resiliency of the ring.
